UNITED STATES PATENT OFFICE.

MICHAEL L. TRIVISONNO, OF CLEVELAND, OHIO.

HAT.

1,162,824.

Specification of Letters Patent. Patented Dec. 7, 1915.

Application filed October 28, 1914. Serial No. 369,012.

To all whom it may concern:

Be it known that I, MICHAEL L. TRIVISONNO, a subject of the King of Italy, residing at Cleveland, in the county of Cuyahoga and State of Ohio, have invented a new and useful Improvement in Hats, of which the following is a specification, the principle of the invention being herein explained and the best mode in which I have contemplated applying that principle, so as to distinguish it from other inventions.

This invention is associated with a hat and particularly with the construction and formation thereof whereby the portions of the head against which it is adapted to be seated are definitely prescribed and limited.

The object of my invention is to provide a head apparel which will not cause baldness.

It is an established though not generally known fact that the permanent loss of hair from the scalp is (pathological and inherent conditions being not unfavorable) attributable to the need, custom or fashion of wearing hats, especially such as tightly bind or firmly wedge the head. This deplorable circumstance is owing to the continued reduction in the supply of nourishment which nature intended to have supplied to the follicles. The hat-sweat of the ordinary type of hat in vogue today is caused to rest upon the wearer's head some little distance above the ears and around in both directions between these organs. In this position the hat-sweat loop crosses the four largest of

the superficial blood vessels of the human head, namely: the right and left occipital and the right and left temporal which latter have posterior and anterior branches. While the blood vessels of the head as elsewhere inosculate quite generally with respect to each other, the two pairs just mentioned are the principal factors in the plexus which is designed to afford circulation about the vertex of the scalp. If, then, the blood circulation were even so much as regularly hindered by compression of certain of these vessels against the skull, the vitality of the hairs around the crown of the head might logically be expected to diminish.

Their vitality is diminished and progressively so

until they fall away. The following readily verified statements attest the soundness of the theory here advanced: There are far fewer bald women. Hatfree men are very seldom bald. Men are habituated to wearing hats tightly compressed against the head. Men quite generally become bald only above the line of hat constriction. A further substantiation may be found by seeking craniums having rather prominent parietal eminences, that is in the region of the superficial temporal blood vessels. In every such case a man nearing middle age can prior to a removal of his hat be safely pronounced as suffering from incipient baldness. If therefore a hat be constructed to fit the head with sufficient firmness and yet avoid compressing any or all of the more important superficial blood vessels of the scalp, notably such as are directly tributary to the temporal and occipital arteries and veins, the attainment of my inventive object will be assured. My inventive conception is associated with means which are hereinafter explained and variously combined in the claims.

While the annexed drawings and particular description thereof, set forth in detail the preferred and modified forms embodying my invention, it should be understood that the means only exemplify some of several diversified mechanical forms with which the principle of my invention may be properly applied.

Adverting to the drawings:—Figure I is a perspective view of a common type of hat. Fig. II is a top view of a hat, embodying my invention applied to the outline of a head and with the crown cut away. Fig. III is a section on line VI—VI of Fig. V. Fig. IV is a view corresponding to Fig. V of a simplified modification.

The object of my invention is to provide a hat which even if very firmly seated upon the head will not compress against the skull of the latter, the temporal and occipital blood vessels, to lessen the natural and necessary amount of flow therethrough.

I would have it understood that while the hat shown in Fig. I is of the conven-

tional or derby type, such is merely an exemplifying form. I have designated the crown of the hat as 1, and the brim as 2. According to my invention, the inner or 5 smaller edge of the brim is provided with a plurality of outwardly extending recesses. Two of such recesses 3, are of considerable extent and follow around the parietal eminences. The other two recesses 4 in the 10 edges of the brim are somewhat smaller and are located to the rear at the point of intersection of the occipital blood vessels with the imaginary line of hat construction. In the preferred embodiment of my invention, 15 I elect to have portions of the crown of the hat corresponding to the brim recesses of differing, softer and in fact of elastic material. A pair of such special crown insert portions 5 and 6, are supplied 20 on each side at forward and rearward points respectively. They extend upwardly above the hat band from the lower edge thereof to otherwise correspond, however, with the recesses 3 and 4 respectively. The 25 reason for these elastic inserts 5 and 6, which are perhaps best seen in Fig. I, is to provide a covering for these side portions of the head which are traversed by the blood vessels stated and which covering 30 will serve as a connecting medium for the hat structure, capable of yielding outwardly relative to the hat in its entirety. Secured at and extending somewhat above the junction of the crown 1 and brim 2 is an interior hat-band 7 having so called hat-sweat 35 portions which actually engage the head as shown in Fig. III. The hat-band by reason of being sewn or otherwise affixed to the inner edge of the brim is adapted to 40 assume an identical shape therewith. It includes therefore a front sweat 8, a rear sweat 9, and an intermediate sweat portion 10, all of which are intended to abut the head. It also includes two portions 11, 45 corresponding in contour with the recesses 3, and two portions 12 corresponding with the recesses 4. It is manifest therefore that the several separated hat-sweats of a hat embodying my invention, are intended to 50 engage merely the front and rear of the head and in this instance, though optionally, the two intermediate portions which have been designated by the letter I. As an added factor, however, tending to insure 55 the outward spacing of certain craniometrical sections of the interior hat-band from the head and particularly from important superficial blood vessels thereof, I choose to insert between the lowermost 60 edge of the crown as a whole and the hat-band 7, a metal reinforcing and shaping band 13, clearly seen in Figs. II and III. This band 13 may be permanently shaped to assume a configuration best suited to the

particular shape of head of the wearer 65 with consideration of the beneficent purpose of my invention.

The modification depicted in Fig. IV consists in the substitution of a single pair of outward recesses 14 in the brim in place of 70 two pairs and also in the omission of the reinforcing band 13. As so constructed there would be only two side elastic portions 15 corresponding in longitudinal extent with the recesses 14. The hat-band 16 would in 75 this instance firmly engage as hat-sweats only across the forehead at 17 and across the very rear of the head at 18.

I claim:—

1. A hat comprising a brim having its 80 inner edge provided with definitely located recesses and a hat band having portions adapted to occupy said recesses.

2. A hat comprising a crown portion, a brim portion having portions of its inner 85 edge outwardly recessed, said crown having cut out portions correspondingly located at said brim recesses, inserts secured between said crown and brim and of differing texture than said crown portion for the pur- 90 pose specified.

3. A hat comprising a brim having its inner edge fashioned with oppositely disposed outward recesses, a crown having its 95 lower portion of like configuration as such edge, a stiffening band of like configuration as the inner edge of said brim and a hat band above said brim and secured to said stiffening band.

4. A hat comprising a crown having portions of its lower edge recessed, an interior hat band bent outwardly into said recesses, and a stiffening form for maintaining said portion in such position. 100

5. A hat comprising a brim having its 105 inner edge formed at definite craniometrical points with recessed areas, and a crown, the lower edge section of the latter having elastic and non-elastic portions alternately arranged therealong, said elastic portions sub- 110 stantially conforming and secured to said brim recesses.

6. A hat comprising a brim, and a crown, said crown being formed at definite craniometrical points with more flexible portions 115 than at any other points, said more flexible portions extending upwardly above said brim, said portions being normally bent outwardly and adapted to yield still further in an outward direction. 120

7. A hat comprising a crown fashioned along its lower edge with a plurality of outwardly recessed portions, the latter being definitely separated and arranged therearound, a brim carried by such crown and 125 having outwardly recessed portions correspondingly spaced and conforming to said first mentioned recessed portions, and a hat

band of like configuration as and secured along the entire junction of said crown and brim whereby to present separated hat-sweat sections between said recessed portions respectively for engagement with the head of the wearer.

Signed by me this 24th day of October, 1914.

MICHAEL L. TRIVISONNO.
